UNITED STATES PATENT OFFICE.

JOHN LOUCIEN CHESNUTT, OF KANSAS CITY, MISSOURI.

TRUCK.

1,230,278.

Specification of Letters Patent. Patented June 19, 1917.

Application filed July 6, 1915. Serial No. 38,113.

To all whom it may concern:

Be it known that I, JOHN LOUCIEN CHESNUTT, a citizen of the United States, residing at Kansas City, in the county of Jackson and 5 State of Missouri, have invented a certain new and useful Improvement in Trucks, of which the following is a specification.

My invention relates to improvements in trucks.

10 The object of my invention is to provide a truck of novel construction which may be easily turned in a confined space while carrying a heavy load.

Another object of my invention is to provide 15 a lifting truck adapted to move under and lift a heavy load, and which is provided with novel means by which a single operator may easily lift and transport such a load.

20 A further object of my invention is to provide a truck with novel means by which a load may be lifted to and retained at different heights from the floor.

The novel features of my invention are 25 hereinafter fully described and claimed.

In the accompanying drawings which illustrate the preferred embodiment of my invention,

Figure 1 is a plan view of my improved 30 truck, parts being broken away.

Fig. 2 is a side elevation of the same, partly broken away, showing the top frame in the lowermost position and the draft handle in an upright position.

35 Fig. 3 is a side elevation of the truck, partly broken away, the top frame being in the uppermost position, the draft handle being shown in the horizontal position and the oscillatory toothed member shown locked 40 from retraction.

Fig. 4 is a top view of the toothed oscillatory member.

Fig. 5 is an enlarged top view of the rear end of the draft handle and some of the 45 parts connected therewith.

Fig. 6 is an enlarged view, partly broken away, partly in side elevation and partly in vertical section of the forward part of the truck, the top frame being shown in the intermediate position.

Fig. 7 is a bottom view of one of the front supporting wheels and parts connected therewith.

55 Fig. 8 is a central vertical sectional view of one of the front supporting wheels and its supporting frame and a portion of the bottom frame.

Similar reference characters designate similar parts in the different views.

1 designates a bottom frame or wheeled support, upon which is mounted a longitudinally and upwardly movable top or load carrying frame.

The bottom frame 1, adjacent to its rear end, is provided with two supporting wheels 3. The forward part of the frame 1 on its under side is provided with two annular chambers 4, Fig. 8, in which are respectively rotatably mounted, on vertical axes, two circular wheel frames 5, each of which at its 70 upper end is provided with an annular peripheral ball race 6, in which are mounted a series of balls 7, which support the frame 1.

Each of the wheel frames 5 is provided with two parallel vertical flanges 8, Figs. 7 75 and 8, through which extends a horizontal axle 9, disposed at one side, preferably, of the axis of the adjacent frame 5, and which has mounted on it a supporting wheel 10.

In each chamber 4, below the balls 7 and 80 encircling the adjacent frame 5, is an annular row of balls 11, which bear against the inner wall of the chamber 4, and serve as side bearings for the frame 5 adjacent thereto.

85 A horizontal ring 12, detachably secured by screws 13, Fig. 8, to the inner wall of the chamber 4 and encircling the adjacent frame 5 below the balls 11, serves to releasably hold the balls 7 and 11 and the wheel frame 5 in 90 their operative positions.

The frame 1 is provided with two openings 14, through which the upper portions of the swiveled wheels 10 may extend. By means of this construction, large wheels may 95 be employed, and there being no center pivots, the caster wheels 10 will rotate freely on their axes and will very easily swing their respective frames 5, so that the truck may be turned within the length of itself, 100 the disposition of the axles 9 being slightly to the rear of the axes of the frames 5.

In order that the top frame 2 may be lifted with the load, the said frame has mounted on its under side supporting rollers 15 which are respectively adapted to travel upon upwardly and forwardly inclined runways 16, provided on the upper side of the frame 1, two respectively at the rear of the wheels 3 and two at the rear of the wheels 10. The runways 16 are each provided with a longitudinal flange 17. These flanges serve as side guides for the rollers 15.

For the purpose of holding the top frame

from lateral shifting when it has been moved to the uppermost position, shown in Fig. 3, and the rollers are upon the horizontal flat portion of the frame 1, there are provided two brackets 18 secured to and depending from the under side of the top frame 2 adjacent to the rear end thereof.

These brackets are respectively provided with forwardly extending projections 19, which are respectively adapted to enter two horizontal holes 20, Figs. 1 and 3, in the rear end of the frame 1, when the top frame 1 runs out of the runways 16 onto the flat horizontal surfaces 21 on top of the frame 1, as shown in Fig. 3.

For drawing the top frame 2 forwardly from the lowermost position shown in Fig. 2, the following described mechanism is provided.

At the forward end and center of the frame 1 and forming a part thereof is a bracket 22, in which is mounted a transverse horizontal shaft 23 which pivotally supports a toothed oscillatory member 24 provided with a peripheral notch 25 and three peripheral teeth or abutments 26, 27 and 28, Figs. 2, 3 and 6.

A draft handle comprising a yoke 29 secured to the rear end of a tube 30 has the two arms of the yoke pivoted to the shaft 23 at opposite sides respectively of the oscillatory member 24, Fig. 5. Centrally slideable longitudinally in the yoke 29 in a transverse portion 31 which connects the arms of said yoke, is a pawl 32 which is adapted to engage the abutment 26 and to enter the notch 25, when the draft handle is swung to the proper positions.

The yoke 29, forward of the transverse portion 31 is provided with another transverse portion 33 in which the rear end of the tube 30 is secured by a set screw 34.

In the rear end of the tube 30 is secured a plug 35 having an opening through which the forward portion of the pawl 32 extends. Encircling the forward portion of the pawl 32 is a coil draw spring 36 having its ends respectively secured to the tube 30 and to the pawl 32, the tension of said spring normally forcing the pawl 32 to a position in which it will engage with the oscillatory member 24.

When the top frame 2 is in the lowermost position shown in Fig. 2, and it is desired to elevate it, the draft handle is swung to the position shown in Fig. 2, in which position the pawl 32 may be forced by the spring 36 against the oscillatory member 24 and at the rear of the abutment or tooth 26.

Two links 37 are pivoted to the oscillatory member 24, at opposite sides thereof, by means of a transverse bolt 38 which extends through said member. The rear ends of the links 37 are pivoted by a transverse bolt 39 to the forward end and opposite side

respectively of a longitudinal link 40, the rear end of which is pivoted to a bracket 41 by a bolt 41', the bracket being secured to a transverse angle bar 42, which is secured upon the top and forward end of the top frame 2.

With the parts as shown in Fig. 2, if the draft handle be swung forwardly and downwardly, the pawl 32 being engaged with the tooth 26 will rock the oscillatory member 24 clockwise, as viewed in Fig. 2, and, through the intermediacy of the links 37 and 40 and the other parts connected therewith and just hereinbefore described, will cause the top frame 2 to be drawn forwardly, the rollers 15 traveling up the runways 16, thereby elevating the top frame 2 as it moves forwardly.

When the draft handle in its forward movement has reached a substantially horizontal position, the top frame 2 will have been raised to the intermediate position shown in Fig. 6, in which position the rollers 15 are nearly midway of the inclined runways 16.

In order that the weight of the load carried on the top frame 2 shall not force the top frame downwardly, when the pawl 32 is released from the tooth 26, there is provided, Fig. 6, a pawl 43, the lower end of which is pivoted to the bracket 22 and the upper end of which is normally forced to a position in which it will engage the tooth 28 by a coil compression spring 44, the forward end of which bears against the pawl 43 and the rear end of which bears against the bracket 22. When the draft handle has swung the oscillatory member 24 to or past the position shown in Fig. 6, the pawl 43 will engage the tooth 28 and prevent retraction of the oscillatory member 24, thereby preventing downward and rearward retraction of the top frame 2, due to the load carried by said frame.

The draft handle may now be swung upwardly and rearwardly from the horizontal position to an upright position in which the pawl 32 will be forced by the spring 36 into the notch 25. If now the draft handle be swung forwardly and downwardly to the horizontal position, the pawl 32 will rock the oscillatory member 24 clockwise, as viewed in Figs. 3 and 6, and the top frame 2 will be drawn to the position shown in Fig. 3, in which the rollers 15 will be on the flat surfaces 21, and the projections 19 will be in the holes 20. At this time the pawl 43 will engage the tooth or abutment 27, thus holding the oscillatory member 24 from retraction. The truck may now be drawn by the draft handle to any place where it may be desired to discharge the load.

In order to discharge the load and lower the top frame 2, the pawl 43 must be released from the oscillatory member 24, and

said oscillatory member rocked counter-clockwise, as viewed in Fig. 3, to the position shown in Fig. 6. To effect the release of the pawl 43, the following described mechanism is employed.

Pivoted to the outer end of the tube 30 is a bell crank lever having one arm 45 adapted to be engaged with the thumb of the operator, and having an arm 46 which extends into a slot 47 in the outer end of a longitudinal rod 48 mounted in the tube 30, and having at its rear end a lateral arm 49 which is slidably mounted in a slot 50 which is provided in the pawl 32. The rod 48 at its rear end is provided with a lateral arm 52 having a slot 51 in which is slidably mounted one arm of a U shaped member 53, the two arms of which are slidably mounted in a boss 54 on the inner side of one of the arms of the yoke 29, Fig. 6.

The transverse portion of the U-shaped member 53 is adapted to strike against the pawl 43 and disengage it from the oscillatory member 24. To effect this, one arm of the U-shaped member 53 has secured to it a collar 55, Figs. 5 and 6, which is adapted to be struck by the arm 52 and forced rearwardly with the member 53 to a position in which said member will engage and release the pawl 43. To force the member 53 forwardly out of engagement from the pawl 43, it has mounted on one arm a coil spring 56, Fig. 6, the rear end of which bears against the boss 54 and the forward end of which bears against a collar 57 secured to one arm of the member 53.

When it is desired to release the pawl 43, the arm 45 of the bell crank lever at the outer end of the draft handle is swung to the position shown in dotted lines in Fig. 2, thereby forcing the rod 48 rearwardly, thus permitting the pawl 32 to engage the member 24. After this has been done, continued movement of the rod 48 would cause the arm 52 to strike against the collar 55, thus forcing the member 53 against the pawl 43, thereby further compressing the spring 56 and releasing the pawl 43 from the tooth 27 or 28 with which it may be engaged. In the meantime, the parts being as shown in Fig. 3, with the exception that the pawl 32 will be in the notch 25, the member 24 may be oscillated counter-clockwise, as viewed in Fig. 3, by swinging the draft handle from the horizontal to the upright position, at which time the member 24 will be in the position shown in Fig. 6, with the pawl 43 again engaged with the tooth 28.

Upon now swinging the arm 45 of the bell crank lever to the position shown in Fig. 3, the rod 48 will be drawn forwardly, the arm 52 thereof will release the collar 55, and the arm 49 will draw the pawl 32 out of the notch 25. The draft handle is then swung forwardly and downwardly, and the

bell crank lever arm 45 is swung to the position shown in solid lines in Fig. 2, thereby permitting the spring 36 to again force the pawl 32 into a position in which it will engage the tooth 26. The bell crank lever arm 45 is then swung to the position shown in dotted lines in Fig. 2, thereby still further rearwardly forcing the rod 48, the arm 52 of which will again strike the collar 55 and force the member 53 to a position in which it will release the pawl 43 from the tooth 28. The weight of the load on the top frame 2, which is now in the intermediate position shown in Fig. 6, will force said frame downwardly and will retract the member 24 and 80 with it the draft handle which will again assume the position shown in Fig. 2.

In order that the pawl 32 may be held disengaged from the member 24, so as to permit free swinging of the draft handle, the outer end of the arm 46 of the bell crank lever at the forward end of the draft handle, is provided with a notch 58, Fig. 2, into which the rod 48 is adapted to enter when the bell crank lever is swung to the position shown in Fig. 3. When so positioned, the bell crank lever and the rod 48 are locked together, the tube 30 holding the rod 48 from lateral movement sufficient to permit the rearward swinging of the arm 46 and thus preventing the spring 36 from forcing the pawl 32 into engagement with the oscillatory member 24. When the bell crank lever is so disposed, as shown in Fig. 3, the draft handle may be freely swung to 100 and fro as may be desired.

The oscillatory member 24 is provided with a peripheral notch 59 adapted to receive the bolt 39, Figs. 3 and 6, when the oscillatory member 24 has been swung to a position a little forward of that shown in Fig. 6. This is to enable the member 24 making a straight pull upon the link 40, after said member has been swung to a position, approaching that shown in Fig. 3, in which the links 37 will incline downwardly and forwardly from the horizontal. The notch 59 is so shaped, that the member 24 will bear against the link 40 when the pawl 32 is in the notch 25 and the draft handle is 110 swung upwardly and rearwardly for the purpose of forcing the top frame 2 off from the flat surfaces 21 and onto the inclined runways 16.

My invention is adapted particularly for use in lifting piles of paper which are mounted on elevated platforms, not shown, under which the truck is adapted to be run and which are of such height from the floor that they may be lifted therefrom when the top frame 2 is raised to the position shown in Fig. 3.

In the operation of my invention, the truck, with the parts positioned as shown in Fig. 2, is run under the load which it is de- 130

sired to lift and transport. Preferably the load is disposed on the floor at a height slightly above the top of the frame 2. The lever or draft handle is then swung clockwise from the upright to the horizontal forward position, shown in Fig. 6, thus carrying the oscillatory member 24 to a position which permits the pawl 43 to drop in behind the tooth 28. At this time the top frame, as before described, will be in the position shown in Fig. 6, and the load carried thereby will have been lifted. To still further lift the load, if this should be desired, the draft handle or lever is swung to the position shown in Fig. 2, in which position the pawl 32 will be forced by the spring 36 into the notch 25. The draft handle is then again swung forwardly to the horizontal position. During this movement the links 37 will pass to a forwardly and downwardly inclined position, and the link 40 will enter the notch 59 and engage the periphery of the member 24, thus securing a straight forward pull on the link 40.

25 By the time the draft handle has reached, in its second oscillation, the horizontal position, the top frame 2 and its load will reach the uppermost position, shown in Fig. 3, at which time the pawl 43 will drop in behind the tooth 27 of the member 24. The bell crank arm 45 may now be swung to the position shown in Fig. 3, thereby withdrawing the pawl 32 from the notch 25, if desired, so that the draft handle may be swung 30 freely in transporting the truck to the desired place.

When the load is to be discharged, the draft handle is again swung to a position in which the pawl 32 can enter the notch 25, at 40 which time the bell crank arm 45 is swung to the position shown in dotted lines in Fig. 2, thus permitting the pawl 32 to enter the notch 25 and causing the rod 48 to engage and force rearwardly the collar 55 and the member 53, thus releasing the pawl 43 from the tooth 27 with which it is engaged. The draft handle is then swung from the horizontal position upwardly, thereby rocking the member 24 counter-clockwise, as viewed 45 in Fig. 3, and causing said member to engage the end of the link 40, thereby forcing the top frame 2 and the load rearwardly, the forward and rear rollers 15 running off from the horizontal surfaces 21 and down the runways 16 to the position shown in Fig. 6, at which time the pawl 43 will engage the tooth 28, thereby holding the top frame 2 and the load from further downward movement, until the draft handle has been 50 released, in the manner described, from the member 24 and swung to the forward horizontal position. At this time the bell crank arm 45 is again operated to release the pawl 32 and permit it to engage with the tooth 55 55 26. At the same time the rod 48 will be

forced rearwardly to a position in which the member 53 will release the pawl 43. The weight of the load on the top frame 2 will now force the said frame downwardly to the position shown in Fig. 2, the operator 70 holding back on the draft handle to prevent too sudden a descent of the load.

The platform, not shown, which carries the load, will now be resting upon the floor, and the truck may be withdrawn for use 75 elsewhere.

Upon the upper side of the frame 1 at the forward end thereof, and adjacent to the forward corners respectively of said frame, may be provided two upwardly extending 80 lugs 60 over which the forward end of the frame 2 is adapted to pass, and which are respectively adapted to engage the opposite inner sides of the frame 2, for holding the latter against lateral movement at its forward end when the forward rollers 15 pass from the runways 16 onto the forward flat horizontal surfaces 21.

I do not limit my invention to the structure shown and described, as modifications, 90 within the scope of the appended claims, may be made without departing from the spirit of my invention.

What I claim is—

1. A truck provided with a top frame and a bottom frame, an oscillatory member pivoted to one of said frames, means actuated by said oscillatory member for lifting the top frame when said member is swung in one direction, releasable means for holding 95 said member from retraction after it has been swung in said direction to a predetermined position, a draft handle pivoted to one of said frames, releasable means actuated by the draft handle for engaging and swinging said oscillatory member, and means, operable only when said swinging means is engaged with said member, for releasing said holding means from said member. 100

2. A truck provided with a top frame and a bottom frame, an oscillatory member pivoted to one of said frames, and provided with an abutment and a notch, a draft handle pivoted to one of said frames independently of said member, means actuated by said member for lifting the top frame when said member is moved in one direction, a pawl carried by said draft handle and adapted to consecutively enter said 110 notch and engage said abutment for consecutively swinging said member to two positions when said handle is oscillated, means for releasably holding said member from retraction from either of said two positions, and means operable only when said pawl is engaged with said abutment or is in said notch for releasing the holding means from said member. 115

3. A truck provided with a top frame and 120

- a bottom frame, an oscillatory member pivoted to one of said frames, a draft handle, means actuated by the draft handle for swinging said member, draft means connecting said member and said other one of said frames for moving the top frame longitudinally when said member is swung in either direction, said draft means having bearings at different points on said member when the member is in certain different positions, and means supported by the bottom frame and supporting the top frame by which the top frame is moved upwardly when it is moved longitudinally of the bottom frame.**
- 4. A truck having a top frame and a bottom frame, an oscillatory member pivoted to one of said frames, means actuated by said member for lifting the top frame when said member is swung in one direction, a draft handle pivoted to one of said frames, a pawl for holding the oscillatory member from retraction, controlling means carried by the handle for forcing said pawl out of engagement with said member, means for forcing said controlling means into operative engagement with said pawl, a second pawl carried by said handle and adapted to engage with said member, and manually operated means carried by said handle for simultaneously withdrawing the second pawl from engagement with said member and for withdrawing said controlling means from engagement with the first named pawl.**
- 5. A truck having a top frame and a bottom frame, an oscillatory member having a notch, two links respectively pivoted to the oscillatory member and to said top frame and pivoted to each other, one of said links being adapted to enter said notch and operatively engage said member so as to be moved longitudinally of the bottom frame thereby when the links are out of alinement with each other, and means for oscillating said oscillatory member.**
- 6. A truck having a top frame and a bottom frame, an oscillatory member carried by one of said frames and having a ratchet tooth and a notch, a draft handle pivoted to one of said frames, means connecting one of said frames and the oscillatory member by which the latter when swung will move the top frame longitudinally of the bottom frame, and a pawl carried by said handle and adapted to engage said tooth so as to turn said member in one direction only and adapted to enter said notch and to swing said member in either direction when the handle is oscillated.**
- 7. A truck having a top frame and a bottom frame, an oscillatory member pivoted to one of said frames, a draft handle pivoted to one of said frames independently of the oscillatory member, means by which the draft handle may releasably engage the oscillatory member for turning the latter, and flexible means connecting one of said frames and the oscillatory member and having an inflexible portion adapted to connect the last-named frame with the oscillatory member, whereby the top frame may be forced rearwardly when the oscillatory member is turned in one direction.**
- 8. A truck having a top frame and a bottom frame, an oscillatory member pivoted to one of said frames independently of the oscillatory member, means by which the draft handle may be engaged with and swing the oscillatory member, and two links respectively pivoted to one of said frames and to the oscillatory member and to each other, the oscillatory member having means for operatively engaging the link which is pivoted to the last-named frame, whereby the top frame may be forced longitudinally of the bottom frame when the oscillatory member is turned.**
- 9. A truck having a top frame and a bottom frame, an oscillatory member pivoted to one of said frames, a draft handle pivoted to one of said frames independently of the oscillatory member, means connecting the oscillatory member and one of said frames, whereby the latter may be forced forwardly and rearwardly when the oscillatory member is oscillated, means movable on the handle for releasably locking the latter to said oscillatory member, a pawl carried by one of said frames and adapted to engage said oscillatory member for holding it from movement in one direction, and means carried by the handle for simultaneously controlling the operation of said pawl and said locking means.**
- 10. A truck having a top frame and a bottom frame, an oscillatory member pivoted to one of said frames, a draft handle pivoted to one of said frames independently of the oscillatory member, means connecting the oscillatory member and one of said frames by which the latter may be forced forwardly and rearwardly when the oscillatory member is oscillated, a pawl pivoted to one of said frames and adapted to engage the oscillatory member to hold it from movement in one direction, a pawl carried by the handle and adapted to engage said oscillatory member, means for normally forcing said pawls into engagement with said oscillatory member, and means carried by said handle, which, when moved in one direction, disengages one pawl from the oscillatory member, and when moved in the other direction disengages the other pawl from the oscillatory member.**
- 11. A truck having a top frame and a bottom frame, an oscillatory member pivoted to one of said frames, a draft handle pivoted to one of said frames independently of the oscillatory member, means connecting the os-**

6
 oscillatory member and one of said frames by which the latter may be forced forwardly and rearwardly when the oscillatory member is oscillated, a pawl pivoted to one of said frames and engaging the oscillatory member for holding it from movement in one direction, a pawl carried by the draft handle and adapted to engage said oscillatory member, means for normally forcing said pawls into engagement with said oscillatory member, means including a slidable member mounted on said handle, by which, when the slidable member is moved in one direction, the pawl on the handle will be disengaged from the oscillatory member and when the slidable member is moved in the opposite direction, the other pawl will be disengaged from the oscillatory member, and releasable means for locking the slidable member in a position in which it will hold the pawl carried by the handle disengaged from the oscillatory member said means which includes the slidable member being out of engagement with said other pawl when the slidable member is in said last named position.

12. A truck having a top frame and a bottom frame, an oscillatory member pivoted to one of said frames, a draft handle pivoted to one of said frames independently of the oscillatory member, a pawl carried by

the handle, a spring for forcing said pawl normally into engagement with said oscillatory member, a second pawl carried by one of said frames, a spring for normally forcing the second pawl into engagement with said oscillatory member for holding the latter from movement in one direction, a reciprocative member adapted to be moved into engagement with the second pawl for forcing the latter out of engagement with the oscillatory member, a spring for forcing the reciprocative member normally out of engagement with the second pawl, a slidable member carried by the handle and engaging the first named pawl and said reciprocative member and arranged when moved in one direction to disengage the first named pawl from the oscillatory member and when moved in the opposite direction to force the second pawl out of engagement with the oscillatory member, means carried by the handle for moving said slidable member in both directions, and means connecting the oscillatory member and one of said frames by which the latter may be forced forwardly and rearwardly when the oscillatory member is oscillated.

In testimony whereof I have signed my name to this specification.

JOHN LOUCIEN CHESNUTT.
